APPARATUS FOR DEPOSITING MATERIAL
IN WELL HOLESJames D. Haynes, Kilgore, Tex., assignor to The
Dow Chemical Company, Midland, Mich., a cor-
poration of Delaware

Application January 8, 1945, Serial No. 571,738

11 Claims. (Cl. 166—19)

1

The invention relates to apparatus for depositing liquid materials in deep wells. It more particularly concerns an improved dump bailer apparatus which may be run into a well on a cable, or the like, and operated thereby to completely unload its charge by positive displacement means.

One of the objects of the invention is to provide an apparatus for lowering into deep wells a charge of a liquid agent, the complete displacement of which from the apparatus into the well is assured. Another object is to provide an apparatus of the aforesaid character which protects the liquid charge from contamination with liquids already in the well while being lowered thereinto. Other objects and advantages will appear from the following description of the invention, reference being made to the accompanying drawings in which—

Fig. 1 is a longitudinal sectional view of a preferred form of the invention completely assembled, the discharge valve being in the closed position, the slide valve in the open position, and the piston rod latch in the retracted position.

Figs. 2, 3, 4, and 5 are enlarged cross sections on the lines 2—2', 3—3', 4—4', and 5—5', respectively, of Fig. 1.

Fig. 6 is a fragmentary enlarged view of a portion of the apparatus of Fig. 1 before lowering into the well showing the position of the piston after charging the container with a full load and the piston rod latch in the rod engaging position.

Fig. 7 is a view of the lower portion of the apparatus of Fig. 1 resting on the tail pipe in the bottom of a well, the discharge valve being in the open position and the slide valve closed.

Fig. 8 is a fragmentary sectional view showing a modification of the apparatus of Fig. 1, the discharge valve being in the open position.

Fig. 9 is a cross section on the line 9—9' of Fig. 8.

Fig. 10 is a similar view to that of Fig. 8 showing the apparatus resting on the tail pipe in the bottom of a well, the discharge valve being in the open position.

Like numerals refer to like parts throughout the drawings.

The apparatus illustrated in Figs. 1 to 7, inclusive, comprises a container 11 adapted to hold a quantity of liquid material to be deposited in the well. Its outside diameter is slightly less than that of the well it is to enter and of such length as to hold a suitable volume of liquid. The larger end of a reducing coupling 12 is secured to the upper end of the container 11 by screw threads 13 and serves as the cylinder head,

2

the small end providing an opening to admit the serrated piston rod 14 or ratch, and to support the housing 15 for the piston rod locking spring pawls or fingers 16 and spring pawl or finger release 17. As shown, the housing 15 is internally threaded with a right hand thread and the thread engages the externally threaded portion 18 of the release for the spring pawls. An octagonal head 19 integral with the release is provided for facilitating its rotation and consequent longitudinal movement on the thread inwardly or outwardly of the housing 15. In Fig. 1, the pawl release is shown in the inward position in the housing 15 so as to withhold the pawls 16 from engagement with the serrations 20 of the piston rod. In Fig. 6, the pawl release is shown in the outward position allowing the spring pawls to engage the serrations 20 of the piston rod, preventing its movement outwardly through the cylinder head.

Piston 21, attached to the lower end of piston rod 14, operates within the cylinder 11. Just below the piston 21 (when at the top of the cylinder), the cylinder 11 is provided with a loading port 22 adapted to receive the spout of a funnel 23 for example (see Fig. 1), to facilitate the introduction of a liquid charge into the container or cylinder of the bailer.

The lower threaded end 24 of cylinder 11 engages the valve seating ring 25 having a beveled seat portion 26 and valve port 27 forming a discharge opening for the cylinder. The ring 25 also serves as a coupling or collar in which is secured by screw threads the upper end 28 of the cylindrical slide valve body 29 near the top of which is provided a cleaning port 30.

Valve stem 31, of smaller diameter than the port 27 through which it passes, carries a head portion 32 adapted to seat upon the valve seat 26 to close the port 27. The lower end of the valve stem is attached to the head 33 of a cylindrical slide valve 34 which makes a sliding fit with the inside wall of the cylindrical slide valve body 29. The slide valve 34 co-operates with the valve body 29 to open or close the port 30, which is shown in Fig. 1 in the open position and in Fig. 7 in the closed position, respectively, with respect to this port.

Onto the lower end of the slide valve body 29 is secured a reducing coupling 35, the smaller end of which is machined to serve as a guide for the tail pipe 36 which passes through it in a sliding fit. The upper end of the tail pipe is attached to the bottom 40 of the slide valve 34 and serves to move it either up or down within the housing

29, thereby closing or opening, respectively, the cleaning port 30. The head 33 of the cylindrical slide valve is provided with ports 41 which serve as passages for the liquid charge to flow from the cylinder 11 into the interior of the slide valve 34 and thence into the tail pipe 36 when the slide valve is in the top position, as shown in Fig. 7.

The lower end of the tail pipe 36 is provided with discharge ports 37 in the side wall above the bull plug 38 attached to the lower end of the tail pipe by the collar 39.

The upper end of the piston rod 14 is shown in Fig. 1 attached to a set of jars 42 by a coupling 43, the jars being attached to a cable 44 by a cable socket 45.

In the modification shown in Figs. 8, 9, and 10, the slide valve housing 29 and slide valve 34 of Figs. 1 and 7 have been dispensed with, the lower end of the valve stem 31 being connected directly to the top of the tail pipe 49 of similar construction to that of the tail pipe of Figs. 1 and 7, except that it is provided with ports 50 just below the point of attachment to the valve stem. Replacing the slide valve housing 34 of Figs. 1 and 7 is the bushing 51, the threaded periphery 52 of which engages the lower threads of the coupling ring 25. As shown, this bushing is provided with an annular internally threaded boss 53 which is integral with the lower face of the bushing. The bushing is provided with a central aperture 54 through which valve stem 31 passes and by which it is guided in its longitudinal movement. Portions 55 of the bushing 51 are cut away to provide a passage between the top and bottom of the bushing. The upper externally threaded end of the tubular member 56 engages the internal threads of the boss 53 to which it is thus secured. The member provides a support for the guide collar 57 secured to the lower end of 56. The smaller opening 58 of the guide collar is machined so as to make a close sliding fit with the tail pipe 49 which passes through it.

The method of manipulating the two forms of the apparatus illustrated is essentially the same as regards the steps of charging the container, operating the piston rod and rod latch mechanism, and the expulsion of the charge from the container when the apparatus has been lowered into the well. These manipulative operations are described hereafter first with respect to the specific form illustrated in Figs. 1 to 7, inclusive.

For charging the container with the liquid to be deposited in a well using the apparatus of Figs. 1 to 7, inclusive, the bailer assembly is suspended in a vertical position as shown in Fig. 1 so that the weight of the tail pipe and slide valve 34 is borne by the valve 32 resting on its seat 26 so as to close the discharge port of the cylinder, slide valve 34 thus being in the lower position uncovering cleaning port 30. Pawl release 18 is rotated in a right handed direction on the threads in the housing 15 until it reaches the down position, as shown, so that the annular portion 17 engages the pawls 16 and displaces them from engagement with the serrations 20 in the piston rod 14, thereby allowing the piston 21 to be held at the top of cylinder 11 above the charging port 22. A funnel 23, or the like, is then inserted into the charging port 22 and the charge of liquid poured into the cylinder 11. After charging the cylinder, the funnel is withdrawn and a support 46 placed under the reducing coupling 35. The strain on the cable is released allowing the apparatus to rest upon the support 46. The weight of the piston and piston rod causes the piston to descend

onto the liquid as shown in Fig. 6. Pawl release 18 is then rotated in a left handed direction until it reaches the upper position in the tubular housing 15 so that the annular portion 17 moves away from the pawls 16 allowing them to engage a pair of serrations 20 in the piston rod 14, thereby locking the piston against upward movement relative to the cylinder 11. With piston 21 in this position below opening 22, the liquid charge in the cylinder is sealed against contamination and the apparatus is ready for lowering into the well.

The weight of the apparatus is then taken by the cable 44 and the bailer assembly lowered into the well on the cable. Lowering is continued until the weight of the assembly, borne by the cable, is partially relieved indicating that the tail pipe is resting on the bull plug 38 at the bottom 47 of the well 48. Due to the weight of the rest of the apparatus, it descends so that the bottom 47 of the valve seating collar 25 rests upon the head 33 of the slide valve 34, thereby causing the cylinder discharge port 27 to open and slide valve cleaning port 30 to close, as shown in Fig. 7. With the valve head 32 off its seat 26 and slide valve port 30 closed, a passage is provided for the liquid in the cylinder 11 to flow from it through valve ports 41, tail pipe 36, and ports 37 into the well hole. By further lowering the cable 44 and operating the jars 42, the piston rod 17 and piston 21 are caused to descend in cylinder 11, thereby assuring the expulsion of the liquid charge. As the piston rod descends while the annular portion 17 of the pawl release 18 is in the "up" position, as shown in Fig. 6, upward or reverse movement of the piston is prevented so that during the unloading and withdrawal of the apparatus from the end, the charge cannot re-enter the bailer from the well.

After expelling the liquid charge, the apparatus is withdrawn from the well by pulling it up with the cable and rested upon support 46. The tail pipe and slide valve then may be cleaned by introducing a cleaning fluid through the cleaning port 30 which remains open so long as the tail pipe is allowed to hang free as when the apparatus is suspended from the cylinder or piston rod. The piston may be returned to the top of the cylinder above the loading port 22 turning the pawl release 18 on the threads in the housing 15 so that the annular portion 17 moves into engagement with the pawls 16 disengaging them from the serrations 20 of the piston rod, and then pulling the piston rod outwardly from the cylinder until the piston reaches the top of the cylinder. When the piston has been thus returned to the top of the cylinder, the apparatus is ready for reloading.

The manipulation of the modification of the apparatus illustrated in Figs. 8, 9, and 10 follows substantially the same procedure except that of cleaning the apparatus. For example, after charging the container 11 while the piston is at the top of the cylinder, the piston is then lowered onto the charge in cylinder 11 as shown in Fig. 6 and the piston rod latched against outward movement as already described. The apparatus is then ready for lowering into the well, the lowering being continued until the bull plug 38 rests on the well bottom 47 as shown in Fig. 10. In the position shown, the weight of the apparatus above the tail pipe 49 causes the valve 32 to be lifted off its seat 26 as the apparatus (except valve 32 and tail pipe 49) moves downwardly until the bottom face of bushing 51 abuts the top 60 of the tail pipe 49. The charge liquid passes from the container

11 through the discharge port 27, openings 55, the annular space 59, ports 50 into tail pipe 49 and then through openings 61 into the well hole. The charge is completely expelled from the cylinder by causing the piston to move downwardly with the aid of the jars 42, if necessary, as already described for the preferred form of the device.

Cleaning the apparatus after use may be accomplished by introducing a cleaning fluid into the apparatus through port 22 while the top of the tail pipe abuts the bottom of bushing 51, thus opening discharge port 27, and when the piston is raised to the top of the cylinder. The cleaning fluid then may flow through the cylinder, discharge valve and tail pipe. The cleaned apparatus is made ready for reloading as already described.

Among the advantages of the invention are that the liquid charge is fully protected from contamination by fluids in the well hole; complete expulsion of the charge from the container is assured and return of charge or other fluid thereto is precluded while the apparatus is in the well; by employing a known volume of liquid in the container, the amount deposited in the well can be accurately controlled; and viscous liquids such as some of the synthetic resin-forming liquids, e. g. phenol-formaldehyde resin-forming liquids which are difficult to place in deep wells by usual methods can be readily and accurately conveyed to the bottom of deep wells and deposited therein with the apparatus.

I claim:

1. A bailer for depositing a liquid in a well comprising in combination a container for the liquid, said container having a discharge port in the bottom; a piston operable in the container for expelling the liquid therefrom; a piston rod having one end attached to the piston to operate the same; latch means adapted to engage the piston rod to prevent longitudinal outward movement of the piston rod relative to the container; latch release means adapted to disengage the latch means from the piston rod; a tail pipe adapted to receive and discharge liquid from the container; and a discharge valve linked to the tail pipe and adapted to control the flow of fluid from the cylinder to the tail pipe through said discharge port, said discharge valve being operable by longitudinal movement of the said tail pipe relative to the container.

2. A bailer for depositing a liquid in a well comprising in combination a container for the liquid, said container having a discharge port in the bottom; a piston operable in the container for expelling the liquid therefrom; a ratch having one end secured to the piston to operate the same; pawls adapted to engage the ratch to prevent longitudinal outward movement of the ratch relative to the container; means to release the pawls from engagement with the ratch; a tail pipe in communication with the container and operable to discharge liquid from the container; and a discharge valve linked to the tail pipe and adapted to control the flow of liquid from the cylinder to the tail pipe through said discharge port, said discharge valve being operable by longitudinal movement of the tail pipe relative to the container.

3. A bailer for depositing a liquid in a well comprising in combination a container for the liquid, said container having a discharge port in the bottom; a piston operable in the container for expelling the liquid therefrom; a piston rod having one end attached to the piston to operate the same; means on the other end of the piston rod

for securing the same to a suspension means; latch means adapted to engage the piston rod to prevent longitudinal outward movement of the piston rod relative to the container; latch release means for disengaging the latch means from the piston rod; a tail pipe communicating with the container and operable to discharge liquid from the container; a discharge valve adapted to control flow of liquid from the container to the tail pipe through said discharge port, said discharge valve being operable by longitudinal movement of the tail pipe relative to the container.

4. A bailer for depositing a liquid in a well comprising in combination a cylinder for the liquid, said cylinder having a discharge port in the bottom, a piston operable in the cylinder for expelling the liquid therefrom, a piston rod adapted to operate the piston, a cylinder head having an opening therethrough through which the piston rod extends, a latch means supported by the cylinder head and adapted to engage the piston rod to prevent longitudinal outward movement of the piston rod relative to the cylinder, latch release means adapted to disengage the latch means from the piston rod, a discharge valve in the bottom of the cylinder adapted to control the flow of liquid from the cylinder through the said discharge port, a tail pipe communicating with the cylinder and linked to the said discharge valve to operate the said valve by longitudinal movement relative to the cylinder, said tail pipe being operable to discharge liquid from said cylinder.

5. A bailer for depositing a liquid in a well comprising in combination a cylinder for the liquid; a piston in the cylinder for expelling the liquid therefrom; a piston rod having one end attached to the piston; latch means adapted to engage the piston rod to prevent longitudinal outward movement of the piston rod relative to the cylinder; latch release means adapted to disengage the latch means from the piston rod; a slide valve housing communicating with the bottom of the cylinder and having a cleaning port in its side wall, said cylinder having a discharge port in the bottom forming a passage from the cylinder to the slide valve housing; a slide valve in the slide valve housing adapted to form a closure for the said cleaning port; a discharge valve secured to said slide valve adapted to control the flow of fluid through the said discharge port; a tail pipe operable to discharge liquid from the cylinder, said tail pipe having an end connected to the slide valve, said slide valve having a passage therethrough in communication with the said tail pipe and the slide valve housing to permit the passage of liquid from the slide valve housing to the tail pipe, said cleaning port providing an entrance for the introduction of a cleaning liquid into the slide valve housing, slide valve, and tail pipe when the slide valve is closed.

6. A bailer for depositing a liquid in a well comprising in combination a cylinder for the liquid, said cylinder having a discharge port in the bottom; a piston operable in the cylinder for expelling the liquid therefrom; a piston rod having serrations along the surface to form a ratch, one end of the ratch being secured to the piston; a cylinder head having an opening therethrough through which the piston rod extends; a housing attached to the cylinder head and surrounding the piston rod; pawls in the housing adapted to engage the serrations on the piston rod to prevent longitudinal outward movement of the piston rod relative to the cylinder; means to release the pawls from engagement with the

serrations; a cylindrical slide valve housing communicating with the said discharge port and having a cleaning port in the side wall thereof; a slide valve operable in the slide valve housing to open and close the cleaning port; a discharge port closure attached to the said slide valve adapted to control the flow of fluid through the said discharge port; a tail pipe operable to discharge liquid from the cylinder, said tail pipe having an end secured to the said slide valve whereby longitudinal movement of the tail pipe relative to the cylinder operates the said slide valve and the said discharge port closure, said tail pipe having a passage communicating with the said discharge port, said cleaning port providing an entrance for the introduction of a cleaning liquid into the slide valve housing, slide valve, and tail pipe when the discharge valve is closed.

7. A bailer for depositing a liquid in a well comprising in combination a cylinder for the liquid having a loading port near the top and a discharge port at the bottom, a piston operable in the cylinder for expelling the liquid therefrom, a piston rod having one end attached to the piston, a head on the top of the cylinder provided with an opening through which the piston rod extends, latch means secured to the cylinder head adapted to engage the piston rod to prevent longitudinal outward movement of the piston rod relative to the container, latch release means adapted to disengage the latch means from the piston rod, a discharge valve adapted to close the discharge port, a discharge valve stem on the discharge valve and extending through the discharge port, a tail pipe having one end secured to the said discharge valve stem whereby its longitudinal movement relative to the container moves the said discharge valve to open or close the discharge port, said tail pipe having a passage communicating with the said discharge port.

8. A bailer for depositing a liquid in a well comprising in combination a cylinder for the liquid, a piston operable within the cylinder for expelling the liquid therefrom, said cylinder having a charging port in the cylinder wall below the place occupied by the piston when at the top of the cylinder and a discharge port at the bottom, a piston rod having one end secured to the piston, latch means adapted to engage the piston rod to prevent longitudinal outward movement of the piston rod relative to the cylinder, latch release means adapted to disengage the latch means from the piston rod, a discharge valve adapted to close the discharge port, a discharge valve stem attached to the discharge valve and extending through the discharge port, a tubular extension below the cylinder and having its interior communicating with the discharge port and adapted to form a housing for the discharge valve stem, a tail pipe having one end extending into the tubular extension and secured to the discharge valve stem whereby longitudinal movement of the tail pipe relative to the cylinder operates the discharge valve to open or close the discharge port, said tail pipe having a passage communicating with the said discharge port and being operable to discharge liquid from the cylinder.

9. A bailer for depositing a liquid in a well comprising in combination a cylinder for the liquid, a piston operable within the cylinder for expelling the liquid therefrom; said cylinder having a charging port in the cylinder wall below the place occupied by the piston when at the top of the cylinder and a discharge port at the bottom; a

5 piston rod having one end secured to the piston; latch means adapted to engage the piston rod to prevent longitudinal outward movement of the piston rod relative to the cylinder, latch release means adapted to disengage the latch means from the piston rod; a valve adapted to close the discharge port; a valve stem attached to the valve and extending through the discharge port; a tubular extension below the cylinder having its 10 interior communicating with the discharge port and adapted to form a housing for the valve stem; a tail pipe having one end extending into the tubular extension and secured to the valve stem whereby longitudinal movement of the tail pipe relative to the cylinder operates the valve to open or close the discharge port; a head on the tubular extension having an opening therethrough through which the tail pipe extends in sliding relationship, said tail pipe having a port 15 in its side wall near the point of attachment to the valve stem whereby liquid released through the discharge port enters the tail pipe, said tail pipe being operable to discharge liquid from the cylinder.

20 10. A bailer for depositing a liquid in a well comprising in combination a cylinder for the liquid; a piston operable within the cylinder for expelling the liquid therefrom; said cylinder having a charging port in the cylinder wall below the place occupied by the piston when at the top of the cylinder and a discharge port at the bottom; a piston rod having one end secured to the piston; means attached to the other end of the piston rod for suspending it on a cable; a cylinder head 25 attached to the top of the cylinder having an opening therethrough through which the piston rod extends; latch means supported by the cylinder head for preventing longitudinal outward movement of the piston rod relative to the cylinder; latch release means adapted to render inoperative said latch means; a valve adapted to close the discharge port; a valve stem attached to the valve and extending through the discharge port; a tubular extension below the cylinder having its interior communicating with the discharge port and adapted to form a housing for the valve stem; a tail pipe having one end extending into the tubular extension and secured to the valve stem whereby longitudinal movement of the tail pipe relative to the cylinder 30 operates the valve to open or close the discharge port; a head on the tubular extension having an opening therethrough through which the tail pipe extends in sliding relationship, said tail pipe having a port in the side wall near the point of attachment to the valve stem whereby liquid released through the discharge port enters the tail pipe, said tail pipe being operable to discharge liquid from the cylinder.

35 11. A bailer for depositing a liquid in a well comprising in combination a cylinder for the liquid; a piston operable within the cylinder for expelling the liquid therefrom; said cylinder having a charging port in the cylinder wall below the place occupied by the piston when at the top of the cylinder and a discharge port at the bottom; a piston rod having one end secured to the piston; means attached to the other end of the piston rod for suspending it on a cable; a cylinder head attached to the top of the cylinder having an opening therethrough through which the piston rod extends; latch means supported by the cylinder head for preventing longitudinal outward movement of the piston rod relative to the cylinder; latch release means adapted to render 40

inoperative said latch means; a cylindrical slide valve housing attached to the cylinder and having its interior communicating with the discharge port of the cylinder and provided with a cleaning port communicating with the exterior of the housing near the end attached to the cylinder; a cylindrical slide valve adapted to open and close the cleaning port by longitudinal movement within the slide valve housing; a top end member on the slide valve having ports for the passage of liquid therethrough; a valve closure means carried by said top end member adapted to close the discharge port of the cylinder when the slide valve moves into the position opening the cleaning port; a bottom end member on the slide valve forming a closure therefor; a tail pipe attached to the bottom member and in communication with the interior of said slide valve whereby liquid from the cylinder entering the top end member of the slide valve passes through it into the tail pipe, said tail pipe being adapted to move both the slide valve and the said valve closure means relative to the slide valve housing and cylinder discharge port, respectively, so as to

10

5

close the cleaning port and open the discharge port, respectively, when the weight of the apparatus is borne by the tail pipe, and to open the cleaning port and close the discharge port when the weight of the apparatus is borne by the piston rod, said tail pipe being operable to discharge liquid from said cylinder.
